UNITED STATES PATENT OFFICE

KARL H. WHITNEY, OF KIRKSVILLE, MISSOURI

VIBRATORY APPARATUS

Application filed December 17, 1929. Serial No. 414,758.

My invention relates to improvements in mechanical massage or vibratory apparatus. One of its objects is to provide improved apparatus whereby a deep seated mechanical 5 massage or vibratory movement may be imparted to selected portions of the body of a patient to promote the circulation of the blood and lymphatic fluids of the body for therapeutic purposes. Another object is to 10 provide improved apparatus employing a plurality of pressure pads or equivalent members adapted to operate alternately upon different adjacent portions of the body to apply pressure thereto, thereby causing a to and fro movement of the tissues and fluids of the body 15 adapted to effect a deep seated movement and effect, and a tendency to stimulate and pump or feed the blood and lymph fluids forward in their natural channels, and thereby largely 20 take the place of natural exercise in stimulating and accelerating such natural flow. Another object is to provide means whereby an even positive and soothing vibratory movement 25 of selected portions of the body may be had free from irregular, jerky or intermittent pulsations. Another object is to provide improved means whereby a plurality of pressure pads or similar members may be simultaneously operated relative to a considerable 30 portion of the body. Another object is to provide improved speed changeable and readily controllable apparatus for the above purpose. My invention also comprises certain 35 details of form and arrangement and combination of components, all of which will be fully set forth in the description of the accompanying drawings, in which:

Fig. 1 is a side elevation of a patient supporting table with my improved apparatus applied thereto, and illustrating one position of a patient thereon.

Fig. 2 is a view similar to Fig. 1, illustrating a different position of a patient thereon.

Fig. 3 is a perspective view of the table and apparatus shown in Figs. 1 and 2 with the patient omitted.

Fig. 4 is a vertical longitudinal section taken on line 4—4 of Fig. 3.

Fig. 5 is a transverse section through the table, taken on line 5—5 of Fig. 3.

Fig. 6 is a bottom plan view of a portion of the table and driving mechanism.

Fig. 7 is a sectional detail of a portion of the driving mechanism together with the speed changing and controlling clutch mechanism.

Fig. 8 is a perspective view of the driving and speed changing mechanism detached.

Heretofore the application of mechanical vibratory movement and massage has been of a superficial nature, and was not sufficiently deep seated in its nature and effect to have any material influence upon the flow of blood, or lymph fluids except substantially at the surface of the body. Also the movements of the mechanism and body tissues were not firm, slow and uniform, and alternately applied at different localities, and hence were not of a nature to materially stimulate or accelerate a flow of these fluids along their natural channels.

The accompanying drawings illustrate one embodiment of my invention in which 15 represents a table or similar support for a patient. This support is preferably arranged to support the patient either resting thereon face upwardly substantially as shown in Fig. 1 or resting thereon face downwardly as shown in Fig. 2, for which purpose the table is provided with a slit or perforation 16 opposite the face of the patient, to enable the patient to conveniently inhale and exhale air through said perforation. Notches 17 are 20 also preferably provided in the opposite edges of the table adjacent to the shoulders of the patient to receive the upper arms of the patient when facing downwardly. Handles or hand rests 18 are also preferably provided and attached to two of the legs 19 of the table at the head thereof to afford a rest or support for the hands and arms of the patient when facing downwardly. Slots 20 and 21 are also provided along the sides of the table in which 25 slots are mounted a series of short rollers 22 journaled in journal brackets 23 attached to the table top.

Located beneath the table top is a frame or housing 24 in which are mounted a prime mo-

tor or driving member 25, an electric motor for instance, and a plurality of countershafts 26 and 27. The countershaft 26 is driven at a reduced rate of speed by means of a belt 28 from a pulley 29 on the shaft of the motor to a pulley 30 in the countershaft 26. The countershaft 26 is provided with two belt pulleys 31 and 32 of relatively different diameters. The pulley 31 drives a pulley 33 provided with a clutch member 34 and mounted loosely upon the shaft 27 by means of a belt 35 or equivalent driving means. The pulley 32 drives a pulley 36 having a clutch member 37 and mounted loosely upon the shaft 27 by means of a belt 38 or equivalent driving means. A clutch member 39 is splined to the shaft 27 intermediate of the clutch members 34 and 37, and is adjustable endwise of the shaft 27 to engage the clutch member 39 either with the clutch member 34 to drive the shaft 27 at a slow rate of speed, or to engage the clutch member 39 with the clutch member 37 to drive the shaft 27 at a higher rate of speed. The clutch member 39 also has an intermediate position of engagement with both clutch members 34 and 37, in which the shaft 27 is not driven, but remains idle. The clutch member 39 is provided with an annular groove 60, which is engaged by the forked end of a clutch shifting lever 61, pivotally mounted relative to the table 62. A notched segment 63 serves to engage and retain the shifting lever 61 resiliently in its respective positions of adjustment. The shaft 27 has mounted rigidly thereon a crank wheel 40 having a crank pin 41, to which is pivotally attached a link or connecting rod 42. The opposite end of the connecting rod 42 is pivotally attached at 43 to a stud carried rigidly by a bar 44 which is mounted in housings or guides 45, 46 and 47 to reciprocate endwise thereof. Each of the guides or housings 45, 46 and 47 is provided with two rocker arms 48 and 49, and with two sets of rollers or pulleys 50 and 51. A section of belting or cable 52 is attached at one end to an eye in one end of the rocker arm 48 and its opposite end is attached to an eye in one end of the rocker arm 49. The cable 52 is attached at an intermediate point 53 to the bar 44. The cable 52 is also trained over the pulleys 50. Another section of belting or cable 54 is attached at one end to an eye in the opposite end of the rocker arm 48, and the opposite end of the cable 54 is attached to an eye in the opposite end of the rocker arm 49. The cable 54 is trained over the pulleys 51 and at an intermediate point 55 is attached to the bar 44. The respective rocker arms 48 and 49 are centrally pivoted at 56 to the housing 45, 46 or 47. Thus when the bar 44 is reciprocated endwise the respective rocker arms 48 and 49 of each housing 45, 46, and 47, are rocked upon their pivots 56, to and fro. 65 Straps or harness members 57 and 58, each

provided with a series of perforations to receive a buckle tongue are attached respectively to the eyes at opposite ends of the respective rocker bars 48. These harness members 57 and 58 are drawn upwardly from the rocker arms 48 through the slot 21 in the edge of the table and over the rollers 22 in the slot 21. The harness members 57 and 58 are then drawn across the body of a patient resting upon the table 15, and into grooves or recess in the upper faces of pads 64 and 65 resting upon the body of the patient. Harness members 66 and 67 are respectively attached at one end to eyes in the ends of the respective rocker arms 49. The harness members 66 and 67 are passed from the rocker arms 49 upwardly through the slot 20 and over the rollers 22 mounted therein, and above the table top are provided with strap buckles 68 by which the free ends of the harness members 57 and 58 are attached respectively to the free ends of the harness members 66 and 67, with any desired degree of tension or strain exerted upon the pads. The action of the reciprocating bar 44, cables 52 and 54, rollers 50 and 51, and rocker arms 48 and 49 upon the harness members and pads 64 and 65, operating in pairs is such that the rocker bars 48 and 49 are rocked in pairs in reverse directions so as to pull the harness members 57 and 66 and pad 64 in one direction, for instance toward the slot 20, while the harness members 58 and 67 and the pad 65 are at the same time drawn toward the slot 21, thereby applying a peculiar strain upon those portions of the body of the patient adjacent to the pads, which is peculiarly adapted to stimulate and accelerate a flow of blood and lymph fluids in the tissues so influenced, and so as to have a deep seated as well as a superficial stimulating and accelerating result. The adjacent harness members of adjoining pairs of said harness members are actuated by different adjacent rocker bars also move in opposite directions to thereby attain a similar stimulating effect, between alternate harness members where four, six or if desired more than six harness members are employed simultaneously. It will be noted that the entire train of operating members applying energy to the patient, comprising the harness, the rocker bars, and the connecting cables are practically unyielding in nature, and that whatever there may be of a resilient nature must reside in the body of the patient which is inclosed within the loop formed by the harness, the rocker bars and the cables. Also that by tensioning or tightening this loop about the body the result may be varied and made more or less deep seated in its influence. 115

The rollers 22 take the strain of the harness at the sides with an antifriction movement, causing the tension and strain of movement to be concentrated largely upon and in the 130

neighborhood of the pads 64. The side bars 72 of the table conceal the operating mechanism from view, and are preferably detachably mounted. With my improved apparatus practically the entire length of the spinal column may be under treatment at the same time, and the treatment may be conveniently continued for considerable periods of time, if desired.

10 I have illustrated two rates or changes of speed, but a greater number of speed changes may be provided, if desired. The speed changing and actuating apparatus is comparatively inexpensive and also practically noiseless, and readily kept in operative condition.

15 The apparatus herein shown and described is capable of considerable modification within the scope of the claims without departing from the spirit of my invention.

20 What I claim is:

1. Vibratory apparatus comprising a support for the body of a patient, a motor driven member located beneath and lengthwise of 25 said support and reciprocating endwise thereof, a pair of rocker arms located upon opposite sides of said reciprocating member and actuated thereby, harness members attached to the ends of said rocker arms and forming 30 loops over the body of a patient resting upon said support.

2. Vibratory apparatus comprising a support for the body of a patient, a motor driven member located beneath and lengthwise of 35 said support and reciprocating endwise thereof, a pair of rocker arms located upon opposite sides of said reciprocating member and actuated thereby, harness members attached to the ends of said rocker arms and forming 40 loops over the body of a patient resting upon said support, said harness members moving alternately in opposite directions transverse- ily of the patient.

3. Vibratory apparatus comprising a support for the body of a patient provided at 45 opposite sides thereof with rollers, a pair of centrally pivoted motor driven rocker arms, a pair of harness members each attached at its opposite ends to one end of each of said rocker arms, said harness members being looped over 50 the body of a patient resting upon said support, and movable in opposite directions over said patient.

4. Vibratory apparatus comprising a support for the body of a patient provided at 55 opposite sides thereof with rollers, rocker arms centrally pivoted in pairs to the under face of said support and motor driven, a pair of harness members attached in pairs to opposite ends of said rocker arms, said harness members being looped over said rollers and over the body of a patient resting upon said support and movable in opposite directions over said rollers and patient.

5. Vibratory apparatus comprising a sup-

port for the body of a patient having rollers at the sides thereof, a pair of rocker arms located beneath said support and each centrally pivoted, a driving motor operatively connected to said rocker arms, speed changing apparatus interposed between said motor and said rocker arms, a pair of harness members attached in pairs to opposite ends of said rocker arms, said harness members being looped over said rollers and over the body of 75 a patient resting upon said support, and movable over said rollers and patient in opposite directions.

6. Vibratory apparatus comprising a support for the body of a patient, a pair of loop shaped harness members operating in alternate directions and looped over the body of a patient resting upon said support, a harness driving motor, a pair of speed changing members driven from said motor and operatively connected to said harness members to actuate said harness members at relatively different rates of speed, and a manually operable clutch member having a neutral idle position of adjustment and operative positions of adjustment at opposite sides of said neutral position serving to connect said motor in driving relation with said harness members at relatively different speed 90 ratios. 95

7. Vibratory apparatus comprising a support for the body of a patient, a pair of loop shaped harness members operating in alternate directions and looped over the body 100 of a patient resting upon said support, pads interposed between said harness members and the body of the patient, a harness driving motor, a pair of speed changing members driven from said motor and operatively 105 connected to said harness members at relatively different rates of speed and a manually operable clutch member having a neutral idle position of adjustment and operative positions of adjustment at opposite sides of said neutral position serving to connect said motor in driving relation with said harness members at relatively different speed 110 ratios.

8. Vibratory apparatus comprising a patient support, a frame mounted on the under side of said support, rocker arms spaced apart and pivotally mounted on said frame, a plurality of pulleys mounted on said frame between said rocker arms, cables each attached to certain ends of said rocker arms and passed partially around certain of said pulleys, harness member attached to said rocker arms and extending up over said patient support, and a reciprocating member attached to central portions of said cables and adapted to pull on certain portions of said cables. 115 120 125

9. Vibratory apparatus comprising a patient support, a motor driven member movably mounted on said patient support, a 130

plurality of pulleys disposed in sets with one pulley of each set disposed on the opposite side of said motor driven member from the other pulley in said set, a plurality of cables each passing partially around the pulleys in one set of said sets of pulleys and having its central portion attached to said motor driven member, and harness members operatively connected to said cables and disposed over said patient support.

10. Vibratory apparatus comprising a patient support, a plurality of cables disposed under said patient support, rollers mounted on the under side of said patient support, harness members operatively connected to said cables, passing partially around said rollers and up over said patient support, pulleys mounted on said patient support and disposed in sets with one of said cables passing partially around the pulleys in one set of said pulleys, and a motor driven member movably mounted on said patient support and attached to central portions of all of said cables.

25. In testimony whereof I have affixed my signature.

KARL H. WHITNEY.
